UNITED STATES PATENT OFFICE.

JACOB RUSH SNYDER, OF PITTSBURGH, PENNSYLVANIA, ASSIGNOR TO PITTSBURGH AIR BRAKE COMPANY, OF PITTSBURGH, PENNSYLVANIA, A CORPORATION OF PENNSYLVANIA.

LOCOMOTIVE AND TENDER DISTRIBUTING-VALVE.

1,250,688.

Specification of Letters Patent. Patented Dec. 18, 1917.

Application filed February 13, 1914. Serial No. 818,572.

To all whom it may concern:

Be it known that I, JACOB RUSH SNYDER, a resident of Pittsburgh, in the county of Allegheny and State of Pennsylvania, have invented a new and useful Improvement in Locomotive and Tender Distributing Valves, of which the following is a specification.

This invention relates to a triple or distributing valve for the locomotive and tender brakes.

The object of the invention is to provide a valve for this purpose which is capable of securing a quick service and high braking pressure without danger of inadvertently going to emergency application position and producing an emergency application of the train brakes, and also one in which the complete operation of the engine and tender brakes can be secured without venting the train pipe to the atmosphere, as well as other objects and advantages which will herein-after appear.

In the accompanying drawings, Figure 1 is a longitudinal section through a valve embodying the invention, the section being taken on the line 1—1, Fig. 2; Fig. 2 is a horizontal section through the body portion of the valve casing and bushing on the line 2—2, Fig. 6, and showing the valve seat in plan; Fig. 3 is a vertical section on the line 3—3, Fig. 1; Fig. 4 is a transverse section on the line 4—4, Figs. 1 and 2; Fig. 5 is a section on the line 5—5, Fig. 4; Fig. 6 is an end view of the valve; Figs. 7, 8, 9, 10, 11 and 12 are diagrammatic views showing the valve seat in plan view, the main valve in horizontal section on the line 7—7, Fig. 1 and the graduating valve in horizontal section on the line 7^a—7^a, Fig. 1, and showing different positions of the valve, Fig. 7 showing the same in full release position, Fig. 8 in service application position, Fig. 9 in service lap position, Fig. 10 in overreduction position, Fig. 11 in overreduction lap position, and Fig. 12 in emergency position; Fig. 13 is a plan view of the main slide valve; Fig. 14 is a similar view of a small or graduating valve; and Fig. 15 is a sectional view through the head or cap on a section corresponding to that of Fig. 1, illustrating a modification.

The valve in its general form, construction and arrangement follows the standard Westinghouse and similar triple valves, with

certain modifications therein and additions thereto. It comprises a casing 1 provided on its inner end with a flat face 2 for connection to the auxiliary reservoir and brake cylinder, if desired, and is closed at its opposite end by the head or cap 3. In the casing 60 is the chamber 4 in which works the main piston 5 provided with a stem 6 extending into the chamber or bore 7 of the casing and which stem serves to actuate the slide valves. The auxiliary reservoir is connected to the 65 end of the chamber or bore 7, and is fed through the feed groove 8 in the bushing of piston chamber 4, when said piston is in full release position, all as in the standard type of Westinghouse triple valves. 70

The train pipe connection is through a passage 10 extending longitudinally through the bottom portion of the casing 1 and communicating with passage 11 in the head or cap 3 and which passage in turn communicates with a chamber 12 in the outer portion of the head or cap 3 from which openings 13 provide a communication to the piston chamber 4. 75

In the bore of the valve is a suitable bushing 15 whose lower portion forms a valve seat 16 which is provided with the ports and passages shown in Fig. 2, to-wit,—a small exhaust port 17 communicating with a passage 18 leading to the atmosphere; a 80 pair of small ports 19 and 20 longitudinally in line with the exhaust port 17 and connected by a cored-out passage or groove 21; a small port 22 which communicates with a passage 23 leading to a double-heading control valve (that is, a valve for controlling communication between the main reservoir and train pipe when the engine is second or subsequent in a multiple header), all of which said ports are located on one side of 85 the longitudinal center line of the valve seat, and with the following ports and passages on the opposite side of the longitudinal line of the valve seat, to-wit,—a port 25 communicating with a passage 26, which said 90 passage extends partly around the bushing 15 and communicates with a longitudinal passage 27 leading to the application chamber; a port 28 longitudinally in line with port 25 and adjacent thereto and communicating with the passage 29 which is connected to a suitable exhaust port in the engineer's brake valve (not shown); a port 30 95 100 105

longitudinally in line with port 28 and communicating through passage 31 with the atmosphere; and a port 32 longitudinally in line with the port 30 and located near the inner end of the valve seat and communicating by a circumferential passage 33 with a longitudinal port 34 leading to a steam cut-off valve, said passage 33 having a branch 36 leading to the emergency vent valve hereinafter described.

The casing 1 is extended on one side to form a casing 38 for a supplemental valve mechanism, said casing 38 providing a chamber 39 for the supplemental valve piston 40, which latter is provided with a stem 41 for operating the supplemental valve 42. The latter valve operates in a chamber 43 having communication through port 44 with a passage 45 extending longitudinally through the casing 1 of the valve and communicating with a suitable reservoir, which preferably will be the main reservoir on the locomotive, but which may be a suitable supplementary reservoir. The valve 42 works on a seat 46 which is provided with the brake cylinder exhaust port 47, and is operated by means of a projection 49 from the supplemental piston stem 41, which projection extends through an opening 50 in the valve seat 46. The supplemental slide valve 42 is provided with a cavity 51 adapted in the proper position to connect the opening 50 in the valve seat with the exhaust port 47. Piston chamber 39 and port 50 communicate directly with the passage 52 which in turn communicates with a passage 53 extending longitudinally through the casing 1 of the valve and connected to the engine and tender brake cylinders. The outer end of the supplemental casing 38 is closed by means of a cap 55 and the chamber 56 between said cap and the outer face of the supplemental piston 40 communicates through the passage 57 with the passage 27 leading to the application chamber.

In the head or cap 3 is a passage 60 which communicates at one end with an opening through the emergency valve seat 61 and at its opposite end with an opening through the emergency vent valve seat 62. The emergency valve seat 61 communicates with the train pipe chamber 12 in the head or cap 3 and this communication is controlled by the emergency valve 63 loosely surrounding the graduating stem 64 which is slidably mounted in the head or cap 3 and projects into the piston chamber 4. The outer end of the graduating stem abuts against a spring 65 in the outer closure of the head or cap 3. Said stem is provided with the collar or enlargement 66 which, when the valve is in normal or release position, abuts against the outer face of the emergency valve 63 and assists in holding said valve to its seat, and when said graduating stem is

pushed sufficiently far outwardly said collar or enlargement abuts against the inner face of a sleeve or collar 67 carried by the emergency valve and will unseat said emergency valve, moving the same against the pressure of the supplementary spring 68.

The vent valve seat 62 communicates either with the atmosphere through exhaust port 70, as shown in Fig. 1, or with the brake cylinder passage 53, as shown in Fig. 75. As shown in Fig. 1, the communication between the passage 60 and the exhaust port 70 is controlled by a valve 72 formed on the inner face of piston 73 which works in a chamber 74 into which the passage 36, heretofore referred to, opens at the point 75. The piston 73 is provided with a guiding stem 76 which is surrounded by a light spring 77 which normally holds the valve 72 to the seat 62.

As shown in Fig. 15, the communication between the passage 60 and brake cylinder passage 53 is controlled by a check valve 78 seating toward the train pipe, and normally held to its seat by a light spring 79 surrounding the stem 78a of said check valve.

When the locomotive is single-heading, or is the leading engine of a double-header, it is desirable to lock the valve 72 (or the valve 78, as the case may be), to its seat. To provide for conveniently doing this there is provided a rotatable member or disk 80 provided with an eccentrically located member 81 which is adapted in one position of the member 80 to leave the stem 76 (or stem 78a, as the case may be,) free to move outwardly, but in another position is adapted to contact with the end of said valve stem and hold the valve to its seat. The face of the member 81 is slightly beveled so that it pushes the valve stem inwardly and forces the valve to its seat. The rotatable member 80 is provided with a stem 83 projecting out through a closure 84 and provided on its outer end with a turning member, such as a hand-wheel 85, and some suitable simple locking device indicated at 86. By merely turning the hand-wheel a part rotation, the valves in question can either be locked to their seats or allowed to operate in their intended manners.

Coöperating with the main valve seat 16 is a main slide valve 88 which is held between the piston 5 and collar 89 on the outer end of the piston stem 6, but does not completely fill the space between said piston and collar so that the piston has a limited movement without moving the main slide valve. The upper face of said slide valve forms a seat for the graduating slide valve 90 which is held between collars 91 and 92 on the piston stem 6 and entirely fills the space between said collars so that it moves at all times with said piston. The graduating valve 90 is of the form shown in Fig. 130.

- 14, being substantially T-shaped in plan view, and is provided in its head or longer portion with a cavity 92 extending longitudinally of the valve.
- 5 The main slide valve 88 is provided with the ports and cavities shown in Fig. 13, to-wit, a long, wide cavity 94 extending longitudinally of the valve and located on one side of the center line thereof; a shorter 10 large cavity 95 in line with the cavity 94, an oblong port 96 in line with the cavity 95 and extending entirely through the valve; a long, narrow longitudinal cavity 97 located on the other side of the longitudinal center 15 of the valve and communicating with a port 98 extending through the valve, and a port 99 longitudinally in line with port 98.
- The valve mechanism described has six 20 positions as follows:
1. *Full release position.* (Shown in Fig. 7.)—This position is assumed by the valve upon increase of train pipe pressure for releasing the brakes throughout the train. When this occurs the train pipe pressure entering piston chamber 4 pushes the main piston fully inwardly, as shown in Fig. 1, opening the auxiliary reservoir charging groove 8 and carrying the two slide valves to the position shown in Fig. 7. In this position the application chamber port 25 is connected by the cavity 95 in the main slide valve to the application chamber exhaust port 28, thereby exhausting the application chamber, and also releasing pressure from the chamber 56 on the outer face of supplemental piston 40 by way of passage 57, whereupon brake cylinder pressure acting against the inner face of piston 40 through 25 passages 53 and 52 moves the supplementary valve to the position shown in Fig. 4 in which the cavity 51 of the supplementary valve connects brake cylinder port 50 with exhaust port 47 and exhausts the brake cylinder to the atmosphere. Cavity 94 of the main slide valve also connects steam cut-off valve and emergency vent valve port 32 with the exhaust port 30, thereby venting air from the steam cut-off valve and also venting the chamber 74 on the outer face of the 30 emergency vent valve piston 73 so that said emergency vent valve is held to its seat merely by the spring 77. The double-heading control valve port 22 is connected through port 99 in the main slide valve, 35 cavity 92 in the graduating valve, port 98 in the main slide valve and cavity 97 with the exhaust port 17, thereby exhausting pressure from the double-heading control valve.
2. *Service position.* (Shown in Fig. 8.)—This position is assumed upon service reductions of train pipe pressure, which result in the piston 5 moving outwardly, first moving the graduating valve 90 upon the main slide valve 88, causing cavity 92 in the graduating 40 valve to break the connection between the ports 98 and 99 in the main slide, and to uncover the port 96 through said main slide valve, and then moving the main slide valve until port 96 therethrough registers with application chamber port 25 and also uncovering double-heading control valve port 22, all other ports in the valve seat being blanked with the exception that cavity 94 still connects steam cut-off valve and emergency valve vent port 32 with exhaust port 30. As 45 a consequence auxiliary reservoir pressure flows to the application chamber and through passage 57 to the chamber 56 on the outer face of supplementary piston 40, which results in moving said supplementary piston 50 and slide valve 42 inwardly, thus breaking connection between brake cylinder port 50 and exhaust port 47 and establishing communication between chamber 43 and port 50, whereupon main reservoir air flows from 55 passage 45, port 44, chamber 43, port 50, and passages 52 and 53 to the brake cylinders, and applies the engine and tender brakes. As soon as the brake cylinder pressure is built up to slightly exceed the pressure in chamber 56 the supplementary piston 40 and slide valve 42 move outwardly until communication is closed between chamber 43 and brake cylinder connection 52, but without opening port 50 to exhaust port 47. Should 60 the brake cylinder pressure leak off so as to unbalance the pressures on the opposite faces of the piston 40, the latter will again move inwardly and carry with it the slide valve 42 to admit further pressure from the reservoir 65 to the brake cylinder. Consequently, brake cylinder pressure is maintained uniform entirely irrespective of brake cylinder leakage or variation in piston travel.
- The flow of auxiliary reservoir air to the double-heading control valve causes the latter to close and prevent main reservoir air flowing to the train pipe and defeating the service application. The flow of air from the auxiliary reservoir to the application 70 chamber and double-heading control valve causes such reduction of pressure on the inner face of main piston 5 as to cause said valve to move to the next position, to-wit,
3. *Service lap position.* (Shown in Fig. 9.)—In this position only the graduating valve 90 has moved back until it closes the port 96 through the main slide valve and prevents further air from flowing to the application chamber and therefore stops the brake cylinder application at a pressure corresponding to the extent of train pipe reduction. In this position the double-heading control valve port 22 is still open. The cavity 92 in the graduating valve connects ports 99 and 98 through the main valve, but as these ports do not register with any ports in the valve seat no effect is produced. The communication between the ports 32 and 30 is still maintained.

By successively reducing train pipe pressure the main slide valves can be moved alternately to service position and back again to service lap position as frequently as desired to secure the desired service pressure in the brake cylinders. Each time the main slide valve moves to service position more air is vented from the auxiliary reservoir through port 96 into the application chamber, up to equalization between the auxiliary reservoir and application chamber.

4. Overreduction position. (Shown in Fig. 10.)—This position is assumed by the valve when in making service applications train pipe pressure is reduced to such a degree that the valve moves beyond service position and unless checked is likely to move to emergency application position. This position of the valve provides for venting the pressure from the auxiliary reservoir side of the piston so as to prevent the valve from going to emergency position. In service position the outward travel of the piston 5 is stopped by the graduating stem 64 and without compressing spring 65, but in case the train pipe pressure is reduced to such extent as to be likely to cause the valve to move to emergency position the spring 65 is compressed and the graduating stem 64 moves outwardly until its collar 66 abuts with the sleeve 67, whereupon the resistance of spring 68 is also encountered, which, together with the venting on the auxiliary reservoir side of the main piston, stops the further outward movement of the graduating stem. As soon as the collar 66 abuts the sleeve 67 the slide valves are in such position that the graduating valve has uncovered the port 99 in the main slide valve, and as said port 99 is brought into registration with port 20 in the valve seat, auxiliary reservoir pressure flows through these ports and through passage 21 to port 19, which latter port is lapped by the cavity 97 in the main slide valve, through which the pressure flows and escapes through exhaust port 17. This sufficiently reduces the pressure on the auxiliary side of the main piston so that together with the resistance of spring 68 it not only prevents the valve from going to emergency position, but causes the graduating valve to lap back to the position next to be described.

In this position, also, the double-heading control valve port 22 is still uncovered and ports 32 and 30 are still connected, while port 96 registers with port 28, thus allowing air to flow by way of passage 29 and exhaust by way of the engineer's brake valve (not shown), on the second engine of a multiple header.

5. Overreduction lap position. (Shown in Fig. 11.)—This position is due to the slight venting of the auxiliary reservoir just described, which results in moving the grad-

uating valve inwardly until it covers ports 99 and 96 in the main slide valve breaking the vent connections just described through exhaust port 17 and through the engineer's valve, but without moving the main slide valve or disturbing the other functions described.

6. Emergency position. (Shown in Fig. 12.)—This position is assumed upon a sudden reduction of train pipe pressure which causes the main piston to move fully outwardly, compressing both springs 65 and 68, and in which movement the collar 66 on the graduating stem lifts the emergency valve 63 from its seat. As a consequence train pipe pressure flows from chamber 12 through passage 60, unseating valve 72 and passing to the atmosphere through port 70, as in Fig. 1, or flows past check valve 78 and through passage 53 to the brake cylinder, as shown in Fig. 15. The slide valves are moved fully over, uncovering the double-heading control valve port 22 and the application chamber port 25, thus allowing auxiliary reservoir pressure to flow to the application chamber and cause movement of the supplemental valve as heretofore described for applying the brakes. The cavity 94 has its inner end overlapping port 32 and its outer end extending beyond the outer end of the valve seat 16, so that auxiliary reservoir air will flow to port 32 and from thence to passage 33 to the steam cut-off valve to cut off the steam from the locomotive cylinders, and through passage 36 to the chamber 74 on the outer face of the emergency vent valve piston 73, thereby forcing said valve to its seat after the requisite amount of train pipe reduction.

It will be observed that the double-heading control valve port 22 is connected to the exhaust in full release position, so that normally when the engine is running double header the double heading control valve is open and the main reservoir is supplying the train pipe, thereby assisting the pump on the leading engine, but in all other positions the said double-heading control valve port 22 is opened to admit auxiliary reservoir pressure thereto, thereby bringing about the closure of the double-heading control valve and preventing the reservoir on the second engine from pumping off the brakes.

It will be further observed that in all positions, excepting emergency position, the steam cut-off valve port 32 is connected to exhaust port 30, but that in emergency position port 32 is connected to the auxiliary reservoir, thereby bringing about the cutting off of steam to the engine cylinders in emergency position.

It will be further observed that in full service position the valve has closed the exhaust port 28, which is connected to a suit-

able port in the engineer's brake valve which, when the latter is in running position, is connected to atmosphere. Consequently in service position there can be no 5 venting through this exhaust entirely irrespective of the position of the engineer's brake valve, and consequently the latter on the second or subsequent engine of a multiple header can be left in running position, 10 and not lapped as has heretofore been necessary.

What I claim is:—

1. Air brake valve mechanism having connections to the train pipe, auxiliary reservoir, application chamber and to the atmosphere by way of the engineer's brake valve, and a valve actuated by variations in train pipe pressure and arranged upon increase of train pipe pressure to connect the application chamber to the engineer's valve and 20 on service reduction to connect the auxiliary reservoir to the application chamber and close the connection to the engineer's valve and upon overreduction of train pipe 25 pressure to vent the auxiliary reservoir directly to the atmosphere.

2. Air brake valve mechanism having connections to the train pipe, auxiliary reservoir, application chamber and to the atmosphere by way of the engineer's brake valve, 30 a valve actuated by variations in train pipe pressure and arranged upon an increase of train pipe pressure to connect the application chamber to the engineer's valve and 35 on service reduction to connect the auxiliary reservoir to the application chamber and close the connection to the engineer's valve and upon overreduction of train pipe pressure to vent the auxiliary reservoir 40 directly to the atmosphere, and a supplementary valve device actuated by pressure in the application chamber and arranged to apply and release the brakes.

3. Air brake valve mechanism having connections to the train pipe, auxiliary reservoir, application chamber and to the atmosphere by way of the engineer's brake valve, a valve actuated by variations in train pipe pressure and arranged upon an 45 increase of train pipe pressure to connect the application chamber to the engineer's valve and on service reduction to connect the auxiliary reservoir to the application chamber and close the connection to the engineer's valve and upon overreduction of train pipe pressure to vent the auxiliary reservoir directly to the atmosphere, and a 55 supplementary valve device actuated by pressure in the application chamber and arranged to apply and release the brakes, said supplementary valve device being arranged to maintain brake cylinder pressure against leakage.

4. Air brake valve mechanism having connections to the train pipe, auxiliary reser-

voir, application chamber, a double-heading control valve, and to the atmosphere by way of the engineer's valve, and a valve actuated by variations in train pipe pressure and arranged upon increase of train pipe pressure 70 to connect the application chamber to the engineer's valve and the double-heading control valve to the atmosphere, and on service reduction of pressure to connect the auxiliary reservoir to the application chamber 75 and to the double-heading control valve and close the connection to the engineer's valve.

5. Air brake valve mechanism having connections to the train pipe, auxiliary reservoir, application chamber, a double-heading 80 control valve, and to the atmosphere by way of the engineer's valve, a valve actuated by variations in train pipe pressure and arranged upon increase of train pipe pressure to connect the application chamber to the 85 engineer's valve and the double-heading control valve to the atmosphere, and on service reduction of train pipe pressure to connect the auxiliary reservoir to the application chamber and to the double-heading control 90 valve and close the connection to the engineer's valve, and a supplementary valve device actuated by pressure in the application chamber and arranged to apply and release the brakes. 95

6. Air brake valve mechanism having connections to the train pipe, auxiliary reservoir, application chamber, a double-heading control valve, and to the atmosphere by way of the engineer's valve, a valve actuated by 100 variations in train pipe pressure and arranged upon increase of train pipe pressure to connect the application chamber to the engineer's valve and the double-heading control valve to the atmosphere, and on service 105 reduction of train pipe pressure to connect the auxiliary reservoir to the application chamber and to the double-heading control valve and close the connection to the engineer's valve, and a supplementary valve 110 device actuated by pressure in the application chamber and arranged to apply and release the brakes, said supplementary valve device being arranged to maintain brake cylinder pressure against leakage. 115

7. Air brake valve mechanism having connections to the train pipe, auxiliary reservoir, and application chamber and the atmosphere by way of the engineer's valve and to a double-heading control valve, and a 120 valve actuated by variations in train pipe pressure and arranged in release position to connect the double-heading control valve to the atmosphere and the application chamber to the engineer's valve, and in all application positions to connect the auxiliary reservoir to the double-heading control valve and to the application chamber and to blank the connection to the engineer's valve. 125

8. Air brake valve mechanism having con- 130

nections to the train pipe, auxiliary reservoir, application chamber and atmosphere by way of the engineer's valve and to a steam cut-off valve, and a valve actuated by variations in train pipe pressure and arranged in release position to connect the application chamber and steam cut-off valve to the atmosphere, in service position to connect the auxiliary reservoir to the application chamber and blank the connection to the engineer's valve and maintain the connection of the steam cut-off valve to the atmosphere, and in emergency reduction to connect the auxiliary reservoir to the application chamber and to the steam cut-off valve.

9. Air brake valve mechanism having connections to the train pipe, auxiliary reservoir, application chamber and the atmosphere by way of the engineer's brake valve, an emergency vent valve, and a valve actuated by variations in train pipe pressure and arranged upon increase of train pipe pressure to connect the application chamber to the engineer's valve and vent pressure

from the outer face of said emergency vent valve and upon emergency application of the brakes to connect the auxiliary reservoir to the outer face of said vent valve.

10. Air brake valve mechanism having connections to the train pipe, a reservoir, a brake cylinder and the atmosphere, a movable abutment actuated by variations in train pipe pressure, a valve device controlling a vent from the train pipe and arranged to be operated by movement of said abutment to emergency position, a valve in said train pipe vent arranged to be opened by train pipe pressure, and locking means for said vent valve, comprising a rotatable member and a member carried thereby and arranged to be moved laterally into the path of movement of said vent valve upon actuation of said rotatable member.

In testimony whereof I have hereunto set my hand. 45
